METHOD OF MAKING SHOES.

1,135,953.

Specification of Letters Patent. Patented Apr. 13, 1915.

Original application filed July 29, 1908, Serial No. 445,929. Divided and this application filed December 27, 1910, Serial No. 599,337. Renewed October 26, 1914. Serial No. 868,741.

To all whom it may concern:

Be it known that I, RONALD F. McFEELY, a citizen of the United States, residing at Beverly, in the county of Essex and State of Massachusetts, have invented certain Improvements in Methods of Making Shoes, of which the following description, in connection with the accompanying drawings, is a specification, like reference characters on the drawings indicating like parts in the several figures.

This invention relates to the manufacture of boots and shoes and particularly to methods of making shoes and has for an important object to improve the procedure followed in fitting an upper to a last. The invention will be here explained as applied to the operation of pulling over shoes, this application being a division of my application Serial No. 445,929, filed July 29, 1908. In the pulling over operation it is important to take the stretch out of the upper material while conforming the upper to the shape of the last. This having been done thoroughly and the upper fastened to the sole all along its edge the shoe will retain its original shape without much change during use. If, however, the stretch be taken out of a portion of the upper and not out of an adjacent portion that is subjected to strain during its use, than the shoe will gradually change its shape as it is worn and besides acquiring a baggy, unpleasing appearance will not support the foot as it should do. With these requirements and conditions in mind it is an object of this invention to stretch the upper more thoroughly and uniformly than heretofore and in so doing to distribute the upper stock so that change in form of the shoe during wear will be reduced to a minimum. One step comprised in this improved method consists in seizing the forepart of the upper, including the end and the sides of the toe, and it may advantageously be in a substantially continuous line around the toe from one side to the other, and drafting the entire upper forwardly and preferably also downward along the slope or incline of the instep on the top of the last. By doing this the stretch is taken out of the rear part of the upper, including the lower portion of the quarters as well as the vamp. This is to prevent the bagging of the upper

about the ankle and middle of the foot. It is well understood that the stretch can be taken out of leather by pulling it longitudinally or by pulling it transversely and that having taken out the stretch by pulling it in one direction and securing it little more can be obtained by pulling it in the other direction. While it is possible in making a shoe to stretch the rear and middle part of the upper transversely or toward the sole while the upper is on the last and to fasten it to the sole in this stretched condition the freedom of the top of the shoe in use allows it to draw down and permits the upper to stretch lengthwise as it is worn and thereby become loose about the ankle. As I am advised it has not heretofore been proposed to stretch the full width of the upper lengthwise of the shoe in the thorough manner herein contemplated and results such as are produced in this way have not heretofore been achieved in like degree.

One of the difficulties encountered in pulling over shoes is that the friction of the upper materials upon the last interferes seriously with the freedom of the upper to stretch when it is pulled upon at its edge and consequently the portions of an upper contiguous to its margin are usually pulled hard and sometimes torn without thoroughly stretching a portion of the upper that is remote from the margin and that is free to give up its stretch and become loose when the shoe is put into use. This is particularly noticeable in the forepart of the shoe which it is desirable to stretch thoroughly over the ball in a transverse direction so that the forepart of the foot will be properly confined or braced and prevented from too extensive spreading when the shoe is in use. To obtain freer and more thorough stretching of the upper I propose to hold the sides of the forepart well away from the sides of the last during the initial stretching of the upper both longitudinally and transversely. This reduces to a minimum the frictional adhesion of the upper materials to the last and enables me to stretch the upper over the top of the ball where heretofore greatest difficulty has been experienced. After the initial pull I wrap the upper under tension about the sides of the last and then finally over the edge into position to be secured.

A shoe so made does not retain superfluous leather or stretch where it will work out in the use of the shoe and allow substantial departure from the original lines of the shoe.

5 A very common way to work the upper over the shoe bottom and secure it in lasted position is to wipe it over by the closing and advancing action of end embracing wipers. In practice the advancing action of 10 these wipers tends to a substantial degree to force the marginal and contiguous portions of the upper backwardly at the ends of the wipers and thus create a fullness at the two sides of the forepart. I overcome 15 this difficulty in my new method by pulling the upper forwardly at the sides before the action of the wipers and, it may be preferably, retaining it under forward tension during the overwiping operation. This 20 counteracts the tendency of the wipers to produce fullness at their ends.

There are in use at the present time many lasts of the varieties that have a high toe and a thin ball measurement. With these 25 lasts special difficulty is experienced in getting the upper drawn down into the hollow in the top face of the last back of the high toe. To shape the upper to this type of last I follow the procedure of giving the upper 30 at opposite sides of the toe an extra pull upwardly and preferably slightly forwardly in progressive degree from the front backwards to near the tip seam. By so doing the upper is drawn to the wood of the last 35 on the rear incline of the high toe progressively with the maximum tension at the rear end of the incline. This reduces very much the bridging of the upper over the ball from the toe to the instep which it is so difficult 40 to draw out in pulling the upper at the sides of the ball, which usually follows the pulling at the toe.

To aid in carrying out this invention I prefer to use grippers of a novel construction 45 elsewhere claimed and which comprise curved sectional jaws turning about a center at the middle of the toe and shaped to embrace the end and sides of the toe. By 50 these grippers I seize the upper and hold it outwardly from the sides of the toe while drawing it forwardly and toward the sole to stretch the entire width of the upper lengthwise. I may increase the spread of 55 the portions of the grippers that hold the sides of the upper to reduce the friction on the top of the last while the upper is being pulled; then after the upper has been well stretched over the top face of the last I allow the sides to approach the last and 60 wrap about it and finally wrap the sides over the edge of the last. I exert a forward tension on the upper at the sides of the toe and maintain this tension either by the grippers or otherwise during the inward 65 and backward wiping action of the toe last-

ing wipers. During the latter part of the pulling of the toe portion of the upper I give a progressively increasing upward and preferably forward pull to the upper at the two sides of the toe to tighten it down the rear incline of a high toe and this I do by raising the heels or rear ends of the long gripper jaws with relation to their front ends.

The invention will now be described by 75 the aid of the drawings in which the method is illustrated and the invention will then be more particularly pointed out in the claims.

Figures 1, 2 and 3 are illustrative views of this invention each showing in side elevation and transverse section the toe portion of a shoe in three successive stages of the operation, beginning with the gripping position. Figs. 4, 5 and 6 are other successive views of the same portion of the shoe 85 in plan. Fig. 7 is a diagrammatic view of a gripper and showing in full and dotted lines for comparison three positions, which I have used advantageously in practising the invention. Fig. 8 is a perspective view of 90 said gripper. Fig. 9 shows a shoe.

The upper is seized with the sides of the toe portion in approximately their normal outwardly flared position as shown in Figs. 1 and 4. Preferably the upper is seized on 95 substantially a continuous line along its edge from one side of the toe around to the other side. The entire width of the upper is then pulled forwardly and upwardly whereby the whole upper is stretched longitudinally and tightened about the rear portion of the last and drawn down the usual slope or incline of the instep portion of the last. During this stretching of the upper it is held away from the side faces of the last as 100 illustrated in Figs. 4 and 5 to reduce the area of frictional engagement with the last. In the last part of the pulling movement the sides are carried inwardly toward the last with a wrapping movement of the stretched 110 upper about the last. Also in the last portion of the pulling movement the upward tension on the upper is increased progressively from the front backwardly and there by the upper is drawn down to the wood of 115 the last on the rear incline of the high toe portion.

To aid in the practice of this invention I have employed the illustrated grippers which comprise the long curved jaws 2 120 formed in sections that are relatively movable pivotally at the end of the toe to allow the sections to spread for holding the upper away from the sides of the toe. Each of the sections has a separate carrier 4 which 125 for this purpose turns on a rod 5, the upper portions of the rods being united to move as one device. Each carrier 4 has a lateral finger 6 which, when the grippers are lowered to upper seizing position, seats itself 130

between the inclined walls of a positioning member 8 that is carried on a guide plate 10 that is adjustable transversely of the shoe by a handled segment toothed lever 12. The upper is seized while the gripper sections are in their lowered and outspread positions, as in Figs. 1 and 4 and full lines Fig. 7, the end of the last being positioned against the inner face of the inner jaws as may be seen in Fig. 1 and the tip seam positioned equidistant, or appropriately distanced, from the ends of the gripper sections by the sense of feeling through the operator's fingers. The full width of the upper is then seized as is apparent from Figs. 4, 5 and 6 and the upper is drawn forwardly to take the lengthwise stretch from the vamp and the adjacent portions of the quarters. This forward movement is indicated by comparison of Figs. 1 and 2 and Figs. 4 and 5 and also by the full line and the first dotted line position of the grippers in Fig. 7. With the forward pull, or it may be following it, is an upward pull and by these draftings the upper is drawn down the incline of the instep as down a wedge. The forward pull is obtained by the action of a bar 15 on the gripper rods 5 or on a cam block 16 that is fastened to said rods and rises relatively to the bar 15. The upward pull is derived from a lever 18 connected with the upper end of the rods 5, Fig. 7. During the forward stretching and initial upward stretching the upper is held away from the sides of the last by the action of the positioning members 8 on the gripper sections. During the final updrawing the upper is allowed to draw inwardly and wrap about the sides of the last because the fingers 6 rise out of or into the wider portions of the sockets in the positioning members. The closing of the upper toward the sides of the last may be retarded or delayed until near the maximum tension is obtained, this being done by the use of a spring 20 strung on a rod between the gripper sections. During the final updraw the transverse stretching of the upper over the top of the last is made to increase progressively from the top of the toe toward the ball to draw the upper down to the wood of the last on the rear incline of the toe by raising the heel or rear ends of the gripper sections faster than their front ends are raised. This movement is derived from a fixed stud 24 which is engaged, during the rise of the levers 8 by an inclined guide 25 on the lever, said lever being movable endwise as well as upwardly. This provision gives to the lever and to the upper end of rods 5 the direction indicated by the arrow at the top of Fig. 7. This causes the rods 5 to fulcrum on the roll at the end of bar 15 and raises the heels of the gripper sections faster than their front ends as most clearly shown in Fig. 3. The result-

ing lines of strains are suggested by the arrows on the shoe in Fig. 3. This tightening of the upper over the rear of the toe bends the upper gradually down toward the hollow back of the toe over which it bridges to the instep, see dotted lines Figs. 1 and 2 and makes it easier to draw the upper completely down into the hollow by the side grippers as should be done at the time their operation succeeds the pulling by the toe grippers.

As has been pointed out, the entire width of the upper is seized and pulled longitudinally of the shoe. If it is discovered after the upper has been so pulled that the tip seam is not straight or the throat or lace opening is not correctly positioned on the last, satisfactory adjustment can usually be effected by moving the gripped portion of the upper transversely of the last. This will shift the lace opening laterally and it will increase the forward pull along the side of the last from which the movement takes place, thereby drawing that end of the seam forwardly, while slightly relaxing the pull on the other side of the shoe. The efficiency of this movement for effecting this adjustment is largely due to the fact that the full width of the upper is gripped and shifted as distinguished from a small portion at the toe. The adjusting movement is effected as shown by the handled lever 12.

The forward drafting of the upper at the sides of the toe is preferably maintained during the lasting or overwiping operation of the toe embracing wipers 30 and counter-balances the rearwardly displacing tendency of the rear ends of the wipers, thus preventing bunching of the upper or production of fullness at the sides of the toe. The upper is usually secured in lasted position and under the pulling tension by a thin wire, indicated at 32 in Fig. 3, which is anchored to tacks at each side of the toe and binds the upper against the shoulder of the innersole.

The mechanism that has been here briefly referred to is fully described in said prior application which corresponds to printed British specification No. 17,548/09, to which reference may be had.

Having explained the nature of this invention and described how it may be practised, I claim as new and desire to secure by Letters Patent of the United States:—

1. That improvement in methods of making shoes which consists in initially pulling an upper forwardly down an inclined face on the top of a last and holding the upper outwardly away from the side faces of the last during the forward pull, and then pulling the upper inwardly against the side faces of the last.

2. That improvement in methods of making shoes which consists in pulling an up-

4
per first outwardly in a direction lengthwise of the last and upwardly from the opposite sides of the last to straighten it over the top face of the last, and then continuing 5 the pull upwardly and inwardly to wrap it about the side faces of the last.

3. That improvement in methods of making shoes which consists in pulling an upper lengthwise of the last forwardly and 10 upwardly at the two opposite sides of the fore part of the last while holding it outwardly from the side faces of the last and then permitting it to approach the side faces of the last during a later portion of the 15 pulling movement.

4. That improvement in methods of making shoes which consists in gripping the curved end portion of a shoe upper at the 20 end and opposite sides of the toe of a last, and relatively moving the gripped portions and the last to strain the upper upwardly and longitudinally of the last in a forward direction at the sides and the end of the toe while holding the sides of the toe outwardly 25 away from the sides of the last and thereafter wrapping the upper inwardly over the edge of the last.

5. That improvement in methods of making shoes which consists in gripping the 30 curved end portion of a shoe upper at the end and opposite sides of the toe of a last along a substantially continuous gripping line around the toe while the forepart of the upper is free to be pulled and relatively 35 moving the gripped portions and the last to strain the upper upwardly and longitudinally of the last in a forward direction at the sides and the end of the last.

6. That improvement in methods of making shoes which consists in gripping the 40 curved end portion of a shoe upper at the end and opposite sides of the toe of a last, relatively moving the gripped portions and last in a direction lengthwise of the last to 45 put the upper under tension, holding the gripped portions in position to exert an initial pull outwardly from the side faces of the last and then permitting the said portions to approach the last edge in a subsequent portion of the pulling movement.

7. That improvement in methods of making shoes which consists in gripping the 55 curved end portion of a shoe upper at the end and opposite sides of the toe of a last, pulling said portion lengthwise of the last and upwardly, holding the gripped sections of upper at the sides of the toe outwardly 60 from the edge of the last during the first portion of the pulling movement and permitting said sections to close inwardly toward the edge of the last during the last portion of the pulling movement.

8. That improvement in methods of making shoes which consists in gripping the 65 margin of an upper at the opposite sides of

the toe while the forepart of the upper is free to be pulled, pulling it lengthwise of the last in a forward direction, and, while holding the marginal portion of the upper under forward tension, wiping the upper at 70 the end and sides of the last inwardly and backwardly.

9. That improvement in methods of making shoes which consists in gripping the curved end portion of a shoe upper at the 75 end and opposite sides of the toe of a last, relatively moving the gripped portion and the last to strain the upper upwardly and longitudinally of the last in a forward direction at the gripped points, and then while 80 maintaining the strain in the specified directions at the end and sides of the shoe working the upper into lasted position over the edge of the fore part of the last.

10. That improvement in methods of making shoes which consists in gripping substantially the entire width of the toe portion of an upper, and lengthwise stretching the vamp, including its lower marginal portion, and the lower portion of the quarters and 90 drawing the upper down the incline of the instep by pulling the gripped portion forwardly and upwardly relatively to the toe end of an inverted last.

11. That improvement in methods of making shoes which consists in gripping the toe portion of an upper in a substantially continuous line from one side of the toe around to the other side of the toe and longitudinally stretching the vamp, including its 100 lower marginal portion, and the quarters of the shoe by a forward and upward pull on the entire gripping line at once and then laying the upper under such tension over the last bottom and securing it. 95

12. That improvement in methods of making shoes which consists in gripping an upper at the ends and sides of the toe and holding it away from the side faces of the toe portion of the last, pulling the entire upper 110 forwardly and upwardly to take the stretch from the upper lengthwise of the shoe while the gripped portions are so held, and then wrapping the upper about the side faces of the last and over its edge. 115

13. That improvement in methods of making shoes which consists in gripping substantially the entire width of the toe portion of an upper, and lengthwise stretching the upper so gripped, including the lower portion of the vamp, and then correcting adjustment of the upper by relatively shifting transversely of the shoe the last and the upper so gripped and held under tension, whereby the stretched portion of the vamp 120 along one side of the shoe is further tightened forwardly along the last edge and that on the other side is slightly relaxed while the lace opening is shifted transversely of the shoe. 125

14. That improvement in methods of making shoes which consists in gripping the curved end portion of a shoe upper at the end and opposite sides of the toe of the last, 5 relatively moving the gripped portions and the last to strain the upper upwardly and longitudinally of the last at the sides and end of the last, and progressively increasing the upward tension on the upper from the toe backwardly during the last portion of 10 the pulling movement.

In testimony whereof I have signed my name to this specification in the presence of two subscribing witnesses.

RONALD F. McFEELY.
